US0D1059763S

(12) **United States Design Patent** (10) Patent No.: **US D1,059,763 S**
(45) Date of Patent: ** Feb. 4, 2025

(54) **SLIPPER**

(71) Applicant: **Fuzhou HanGeYi Business Management Co., Ltd.**, Fujian (CN)
(72) Inventor: **Delin Liu**, Fujian (CN)
(**) Term: **15 Years**
(21) Appl. No.: **29/962,643**
(22) Filed: **Sep. 12, 2024**
(51) LOC (15) Cl. 02-04
(52) U.S. Cl.
USPC **D2/916**; D2/919

(58) **Field of Classification Search**

USPC D2/896, 900, 902, 904, 906–908, D2/916–924, 925–945, 946–962, 969–979
